DEEP WELL PUMP

Herman M. Loeber, Beatrice, Nebr., assignor to
Dempster Mill Manufacturing Company, a corporation of Nebraska

Application June 14, 1937, Serial No. 148,184

9 Claims. (CL 103—205)

This invention relates to pumps and pumping devices and more particularly to a pump adapted for deep wells.

An object of this invention is to provide a pump and operating means therefor which is adapted to be positioned in a place subjected to climatic elements and which is so constructed that it will not be adversely affected by climatic conditions.

Another object of this invention is to provide in a deep well pumping device means for compensating slight differences in alignment between the axis of the pumping rod and the guides for the pump reciprocating means.

A further object of this invention is to provide in a device of this kind a housing to enclose the operating parts of the mechanism in order that such parts may be properly lubricated by a lubricant positioned in the housing.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a vertical section partly in detail through the center of a device constructed according to an embodiment of this invention.

Figure 2 is a sectional view taken on the line 2—2 of Figure 1.

Figure 3 is a detail front elevation of the pump operating means with the front shields or covers removed therefrom.

Figure 4 is a sectional view taken on the line 4—4 of Figure 1.

Referring to the drawings, the numeral 10 designates generally a housing which is adapted to have a lubricant positioned therein and the lubricant may be drained out of the housing by removing a threaded plug 13 which is positioned in the lower rear portion of the housing. A shaft 11 is secured in bosses 12 carried by the opposite side walls 14 of the housing 10 and this shaft 11 has a relatively large gear 15 rotatably mounted thereon. A driving pinion 16 is secured to the shaft 17 which is journalled in bearings 18 carried by the side walls 14 in vertically spaced relation to the bosses 12. A relatively large pulley 19 is secured to the shaft 17 and this pulley 19 is positioned exteriorly of the housing 10.

The housing 10 is provided with a closure plate 20 which closes an opening 21 in the upper portion of the housing 10 and this closure 20 is preferably inclined in a rearward and downward direction and is secured by means of bolts 22 or the

like. The closure 20 at its lower rear portion is provided with upstanding lugs 23 which are spaced apart and through which a shaft 24 engages. A plate or platform 25 provided with downwardly extending flanges 26 is disposed in substantially horizontal position and the shaft 24 extends through the rear portions of the flanges 26 to pivotally mount the platform or base 25 on the closure 20. The base or platform 25 is adjusted by means of an adjusting bolt 27 which extends through the forward portion of the base or platform 25 and engages a lug 28 carried by the closure 20.

A motor or power member 29 is secured to the base 25 and is provided with a relatively small driving pulley over which a belt or flexible driving member 30 engages. The belt 30 is trained over the large pulley 19 so that in this manner the speed of the gear 15 is reduced to the desired degree. The housing 10 adjacent the forward end thereof is provided with a pair of spaced apart vertically disposed guide members 31 which, at their lower ends, are positioned in openings 32, provided in bosses 33 and the upper ends of the guide members 31 are secured by means of set screws 34.

Tubular slide members 35 engage the guide members 31 and these tubular slide members 35 are provided at their upper ends with flared portions 36 which provide means whereby the lubricant in the housing 10 may be collected and distributed along the guide members 31 as the slide members 35 reciprocate up and down. Each slide member 35 at substantially the longitudinal center thereof is provided with an enlarged bore 37 within which the lubricant may be retained which is collected by the cups or flared portions 36. The slide members 35 are each provided with a trunnion 38 which is preferably hollow so as to communicate with the lubricating chamber 39 provided by the enlarged bore 37. The trunnions 38 are disposed in alignment and in confronting relation and provide a hollow shaft for a bearing 40 which is integral with a sleeve 41. The bearing 40 contacts both of the trunnions 38 and holds these trunnions in axial alignment.

Each slide member 35 is also provided with a forwardly extending arm 42 having a bearing 43 at its forward end and preferably the two arms 42 are disposed in forwardly convergent relation. A shaft or pin 44 extends through the bearings 43 and a head 45 is disposed between the two bearings 43 and is mounted on the pin or shaft 44. A pump rod 46 is secured to and extends downwardly from the head 45 and is adapted at its

- lower end to be connected to a pumping means disposed within the well casing. A packing 47 is secured to the rod 46 and slidably engages a tubular guide 48 which is secured to a base 49.
- 5 The guide member 48 is preferably of a length slightly greater than the stroke of the slide members 35. The base member 48 is bolted as by bolts 50 to a discharge head or casing 51 provided with laterally extending flanges 52 engaging forwardly
- 10 extending arms 53 integral with the housing 10. The flanges 52 are secured to the arms 53 by bolts 54 or the like.
- The pump rod 46 is reciprocated upon rotation of the gear 15 by means of an eccentric 55 which is secured as by bolts 56 to the gear 15. A sleeve 57 is carried by a ring 58 engaging the eccentric 55 and this sleeve 57 has a lever 59 slidably extending therethrough. The upper side of the sleeve 57 is provided with an elongated channel 60 within which the lubricant is received and lubricating openings 61 extend through the sleeve 57 and communicate with the channel 60 so that the rock arm 59 will be lubricated at all times. The rear end of the rock arm or lever 59
- 20 is secured in a boss 62 carried by a bearing sleeve 63 through which a shaft 64 extends. The shaft 64 is positioned in a rearwardly offset housing 65 integral with the rear wall 66 of the housing 10 and the side walls of the housing 66 are each provided with bosses or bearings 67 in which the shaft or pin 64 is journalled.
- 25 The discharge head 51 is provided with a liquid receiving chamber 68 and has a threaded opening 69 to which the upper end of the well casing
- 30 may be threadedly secured. The chamber 68 is provided with a threaded discharge opening 70 so that the liquid pumped out of the well may be forced through pipes to a collecting means or the like. The base plate 49 is provided with an
- 35 upstanding boss 71 in which the lower end of a pump cylinder 72 is mounted. The cylinder 72 communicates with the chamber 68 through an opening 73 provided in the head 51. A piston rod 74 is secured at its upper end to a forwardly
- 40 extending arm 75 carried by the head 45 and the lower end of the rod 74 has a piston 76 secured thereto. A plate 77 is positioned at the lower end of the cylinder 72 and is provided with suitable openings therethrough so that the air compressed by the piston 76 may be forced downwardly through the opening 73. A spring pressed
- 45 check valve 78 is loosely mounted on a guide rod 79 carried by the plate 77 and this valve 78 opens downwardly to permit the downward movement or passage of air into the opening 73. The upper
- 50 end of the cylinder 72 is open to the atmosphere.
- 55 The forward wall 79 of the housing 10 is provided with an opening 80 which is partially covered by a closure plate or shield 81 fastened to the housing 10 by bolts 82 or the like. The lower end portion of the shield 81 may be bifurcated, as at 83, so that the lower edge of the opening 80 may be engaged therebetween. The shield 81 is provided with a pair of elongated slots 84
- 60 through which the arms 42 are adapted to pass. A shield or plate 85 having a forwardly extending upper end portion 86 is disposed partially about the cylinder 48 and is secured to the cross-head 45 in a position to prevent any water from
- 65 the cylinder 48 leaking into the housing 10 through the slots 84.
- 70 A cover or housing 87 encloses the cylinders 48 and 72 and is provided with a cover 88 which engages over the upper end thereof and which
- 75 also engages an upstanding flange 89 carried by

the forward end of the housing 10. The housing 87 is made removable so that the pump parts positioned therein may be worked upon if necessary.

In the use and operation of this pumping mechanism the motor 29 is adapted to be connected to a suitable source of current supply and rotation of the shaft 80 thereof will effect rotation of the pulley 19. Rotation of the pulley 19 will turn the shaft 17 and the pinion or reduction gear 16 and thus effect rotation of the gear 15. As the gear 15 rotates, the eccentric 55 will rock the sleeve 57 vertically and thus move the rock arm or lever 59 up and down. Movement of the rock arm 59 will effect vertical reciprocation of the crosshead comprising the sleeves 35 and the head 45 and thus vertically reciprocate the pump rod 46 and also vertically reciprocate the piston 76 carried by the piston rod 74. The belt 30 may have the tension thereof adjusted when desired or necessary by turning the adjusting bolt 27 to raise the base 28 and thus move the motor 29 vertically away from the shaft 17. The motor 29 may be removed from the housing 10 by loosening the bolts 22 and removing the cover or closure 20 or, if desired, the motor may be removed by withdrawing the shaft 24 from the upstanding lugs 23.

The provision of a two part crosshead structure embodying the slides 35 and the hollow 30 trunnions 38 is an important feature of this invention as the use of this two part crosshead permits the easier manufacture or construction of the crosshead in addition to the easier assembly and repair thereof. This is the case because the two part crosshead structure, together with the means for pivotally connecting the same to rod 59 and to the pump rod 46, is able to compensate for misalignment of the guide rods 31 with respect to each other and the pump cylinder. 40

It is obvious that various changes and modifications may be made in the details of construction and design of the above specifically described embodiment of this invention without departing from the spirit thereof, such changes and modifications being restricted only by the scope of the following claims.

What is claimed is:

1. A deep well pumping means comprising a pump rod, a housing, a pair of parallel guide members carried by the housing, a slide member on each guide member, confronting trunnions carried by each slide member, a sleeve telescoping said trunnions, a second sleeve carried by said first sleeve and disposed at right angles thereto, a rock lever in said housing slidably engaging said second sleeve, a shaft journalled in said housing, an eccentric carried by said shaft, means engaging said eccentric and said rock lever to rock said lever upon rotation of said eccentric, means for rotating said shaft, and means engageable with the pump rod and said slide members to reciprocate said pump rod upon reciprocation of said slide members.

2. A deep well pumping means comprising a pump rod, a housing, a pair of parallel guide members carried by the housing, a slide member on each guide member, confronting trunnions carried by each slide member, a sleeve telescoping said trunnions, a second sleeve carried by said first sleeve and disposed at right angles thereto, a rock lever in said housing slidably engaging said second sleeve, a shaft journalled in said housing, a gear secured to said shaft, an eccentric carried by said gear, means engaging said eccentric

tric and said rock lever upon rotation of said eccentric, a second shaft journalled in said housing and having an end thereof projecting outwardly of the housing, a gear carried by said second shaft meshing with said first gear, a removable closure carried by said housing, upstanding lugs carried by one end of said closure, a motor supporting platform, means engaging an end of said platform and said lugs to pivotally secure an end of said platform on said lugs, means engaging the other end of said platform and said closure to adjust said other end of said platform relative to said closure, a motor carried by said platform, means engaging said motor and said second shaft to rotate said second shaft, and means engageable with said pump rod and said slide members to reciprocate said pump rod upon reciprocation of said slide members.

3. In a deep well pumping means, a pump rod, 20 a cross-head, a housing provided with a pair of elongated openings in a wall thereof, means carried by said housing and projecting through said openings and engaging said cross-head to reciprocate said cross-head, means securing said cross-head to the pump rod, and a shield carried by said securing means and disposed between said pump rod and said well of said housing.

4. In a deep well pumping means, a pump rod, 30 a housing provided with a pair of elongated openings in a wall thereof, a pair of parallel guide members in said housing adjacent said wall, a slide member on each guide member, opposed trunnions carried by said slide members, means carried by said housing and engaging said slide members for reciprocating said slide members, and means securing the pump rod to said slide members.

5. In a deep well pumping means, a pump rod, 40 means for operating said pump rod and including a pair of parallel guide members and a slide member on each guide member, and a shield carried by said operating means and extending between said pump rod and said slide members.

6. In a deep well pumping means, a pump 45 cylinder, a piston slidable in said cylinder, a pump rod secured to said piston, a housing having an elongated opening parallel to and adjacent to said cylinder, operating means located in said housing and comprising a reciprocating member

extending through said opening and operatively connected to said pump rod, and a shield carried by said member and reciprocable therewith, said shield extending between said cylinder and said opening whereby the pumped fluid escaping from 5 the top of the cylinder cannot enter the housing.

7. In a deep well pumping means, an open ended pump cylinder, a piston slidable in said cylinder, a pump rod secured to said piston, a housing having an elongated opening parallel 10 to and adjacent to said cylinder, operating means located in said housing and comprising a reciprocating member extending through said opening and operatively connected to said pump rod, and a shield carried by said member and extending 15 over the top of said cylinder and between said cylinder and said opening whereby the pumped fluid escaping from the top of the cylinder cannot enter the housing.

8. A pumping mechanism comprising a pump 20 cylinder, a piston slidable in said cylinder, a pump rod secured to said piston, a housing, a pair of parallel guide members carried by said housing, a slide member on each guide member, said slide members being completely independent of each 25 other, means for reciprocating simultaneously said slide members, an arm on each of said slide members, and a pivotal connection between said two arms and said pump rod whereby any relative misalignment of the guide members and 30 the cylinder is compensated for.

9. A pumping mechanism comprising a pump rod, a housing having a pair of elongated openings parallel to and adjacent to said pump rod, a pair of parallel guide members carried by said 35 housing, a separate slide member on each guide member, means for reciprocating simultaneously said slide members, an arm on each of said slide members, each of said arms extending through one of said openings, said arm further having 40 aligned bearings, a shaft extending through said aligned bearings, means connecting said shaft to said pump rod, and a shield secured to said arms and extending between said pump rod and said openings to prevent escaping pumped fluid from 45 entering the housing.

HERMAN M. LOEBER.
